JOHN T. MILLION, OF FAYETTE, MISSOURI.

Design No. 4,495, dated November 29, 1870.

DESIGN FOR SADDLE-TREES.

The Schedule referred to in these Letters Patent and making part of the same.

To all whom it may concern:

Be it known that I, JOHN T. MILLION, of Fayette, in the county of Howard and in the State of Missouri, have invented a new and useful Design in Saddle-Trees; and do hereby declare that the following description, taken in connection with the accompanying drawing, hereinafter referred to, forms a full and exact specification of the same, wherein I have set forth the nature and principles of my said improvement, by which my invention may be distinguished from others of a similar class, together with such parts as I claim and desire to secure by Letters Patent.

The nature of my invention consists in constructing the various parts of which the saddle is composed of the form hereinafter described and shown.

In the accompanying drawing, which illustrates my invention and forms a part of the specification thereof, in which corresponding parts are illustrated by similar letters—

Figure 1 is a plan view of the saddle, and Figure 2, a side elevation thereof.

The construction of my invention is as follows: A saddle of this form is more substantial and simple of construction than those of the ordinary form in use. A A represent the side bars of the tree.

B illustrates the position and form of the seat upon the bars.

Having thus described my invention, I claim—

A saddle of the design and form shown and described.

In testimony that I claim the foregoing, I have hereunto set my hand this 5th day of February, 1870.

JOHN T. MILLION.
